(57) **CLAIM**

I claim the ornamental design for a securing device, as shown and described.

DESCRIPTION

FIG. 1 is a front perspective view of a securing device of the new design;

FIG. 2 is a front elevational view of the securing device of FIG. 1;

FIG. 3 is a rear elevational view of the securing device of FIG. 1;

FIG. 4 is a right side elevational view of the securing device of FIG. 1;

FIG. 5 is a left side elevational view of the securing device of FIG. 1;

FIG. 6 is a top plan view of the securing device of FIG. 1; and, FIG. 7 is a bottom plan view of the securing device of FIG. 1. The portions of the Figures shown in broken lines are for illustrative purpose only and form no part of the claimed design.

1 Claim, 4 Drawing Sheets
